US00D907420S

(12) **United States Design Patent** (10) **Patent No.:** **US D907,420 S**
Liu (45) **Date of Patent:** **** Jan. 12, 2021**

(54) **TABLE BASE**

(71) Applicant: **Foshan Leadex Furniture Co., Ltd.**,
Guangdong (CN)

(72) Inventor: **Anliang Liu**, Guangdong (CN)

(73) Assignee: **FOSHAN LEADEX FURNITURE CO., LTD.**, Foshan (CN)

(**) Term: **15 Years**

(21) Appl. No.: **29/693,592**

(22) Filed: **Jun. 4, 2019**

(30) **Foreign Application Priority Data**

May 7, 2019 (CN) 2019 3 0217854

(51) LOC (13) Cl. **06-06**

(52) U.S. Cl.

USPC **D6/708.23**
